UNITED STATES PATENT OFFICE

HENRY O. ENGSTROM, OF BRIDGEPORT, CONNECTICUT, ASSIGNOR TO THE BRIDGEPORT SWITCH CO., INC., OF BRIDGEPORT, CONNECTICUT, A CORPORATION OF CONNECTICUT

SNAP SWITCH

Application filed April 1, 1930. Serial No. 440,653.

This invention relates to a novel and improved form of snap switch, the novel features of which will be best understood from the following description and the annexed drawings, in which Fig. 1 is a view of the switch from what I shall term the top thereof; Fig. 2 is a section on the line 2-2 of Fig. 3; Fig. 3 is a section on the line 3-3 of Fig. 2; Fig. 4 is a section on the line 4-4 of Fig. 3 and showing the parts in a different position from what they occupy in Fig. 2; Fig. 5 is a section on the line 5-5 of Fig. 3; Fig. 6 is a view corresponding to Fig. 2, but showing a different form of the invention; Fig. 7 is a view on the line 7-7 of Fig. 6; Fig. 8 is an exploded view of a switch showing the relation of the principal parts of the embodiment illustrated in Figs. 1 to 5, inclusive.

Referring first to Figs. 1 to 5, inclusive, the switch comprises a base 1 of insulating material on which is supported the switch mechanism, this mechanism being covered by a cover plate 2. For the sake of convenience I shall refer to this plate as being on top of the base, although it is to be understood that this expression is merely relative, as the switch may be used in any position either horizontal, vertical or otherwise.

A base is provided, with a centrally disposed recess 3 having on opposite walls thereof bearings 4 for the arms 5 of a pivoted member 6 having contacts 7 electrically connected together and each adapted to engage one of the contacts 8 on the base. These contacts 8 are each electrically connected to binding posts 9 which are adapted to receive the usual flexible conductors and therefore the switch is closed when the member 6 is in the position shown in Fig. 4, wherein the contacts 8 are bridged by the member and more specifically by the contacts 7, which are electrically connected together by the member 7. Similarly when the member 6 is moved to the position indicated in Figs. 2 and 3 the switch is opened.

The pivoted bearings 4 are preferably arranged horizontally so that the member 6 will move about a horizontal pivot and the operating means for this movement comprises a

sliding bar 10 which is slidably supported in ears 11 depending from a horizontal plate 12, this plate being thus disposed substantially parallel to the pivot of the member 6. The bar 10 has depending therefrom an ear 13, 55 as best shown in Fig. 8 and this ear is connected to a spring 14 which has its other end bearing against the member 6, the spring having received in this other end the projection 15 on the member 6. 60

This arrangement constitutes a toggle, whereby upon sliding of the bar 10 the member 6 will be operated through the spring 14. The spring will be first compressed and then will snap the switch member 6 from one position to the other. The actuating mechanism for the movement of the bar 10 comprises a cam 16 mounted on an actuating shaft 17 which passes through a collar 18 on the plate 12. The shaft 17 has a portion 19 to which is secured an operating button 20. The cam 16 is received in a recess 21 formed in the top of the bar 10 and is normally in substantially constant engagement with the opposite walls of this recess. By this arrangement it will be seen that rotation of the shaft 17 in either direction will result in operation of the switch through the sliding of the bar 10. The bar may be provided with a plate 22 which is shown as being secured to one end 80 of the bar and bent upwardly so as to extend above the plate 12. This plate 22 has thereon the indications "Off" and "On" and these indications will be located beneath a hole 23 in the cover plate 2 to show the position of 85 the switch.

In Figs. 6 and 7 I have shown a slight modification which corresponds closely to the embodiment just described, except that here the contacts which are to be bridged are shown at 24 and 25 and the member adapted to bridge these contacts is shown at 26. This member has two arms, each adapted to engage one of the contacts 24 and 25 when in the position shown in Fig. 6 and adapted to be moved out of that position to open the switch. In other respects this embodiment corresponds closely to the one first described and similar numerals of reference are used to indicate like parts. The member 26 is secured 100

to a pivot member 6 corresponding in all respects to the member 6 shown in Figs. 2 to 5, inclusive, except in the way in which the contacts are secured thereto.

5 I claim:

1. In a snap switch, a base having spaced contacts thereon, a member pivoted on the base and adapted in one position to bridge said contacts, a plate mounted on the base substantially parallel to the plane of the pivot, a bar slidably supported on the plate and having a recess in one edge thereof, a shaft rotatably mounted on said plate at right angles thereto, and a cam on said shaft received within said recess and engaging the walls thereof.
- 10 2. In a snap switch, a base having spaced contacts thereon, a member pivoted on the base and adapted in one position to bridge said contacts, a plate mounted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft.
- 15 3. In a snap switch, a base having spaced contacts thereon, a member pivoted on the base and adapted in one position to bridge said contacts, a plate mounted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 20 4. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 25 5. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 30 6. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 35 7. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 40 8. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 45 9. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,
- 50 10. In a snap switch, a base having spaced contacts thereon, a member pivoted on the base substantially parallel to the plane of the pivot, ears on the plate extending towards the base and having openings therein, a bar slidably mounted in said openings, a spring connecting said bar to said member and adapted to move the member on its pivot upon movement of the bar, a shaft extending through said plate perpendicular to said bar, a cam on the end of the shaft and disposed in a recess in said bar, and means to rotate the shaft,

HENRY O. ENGSTROM.
